ABSTRACT

There is provided a rotary disc having a plurality of pivotably mounted ice chippers, the extension of the blades of the chippers beyond the periphery of the disc being maintained by rotation of the disc and a fixed or adjustable stop or other means positioned on the disc. The disc is provided with recesses for the blades of the ice chippers in order that they may be retracted into the recesses of the disc if an unusual resistance in the ice is met. Once the resistance has been overcome the cutter returns to its normal position by centrifugal forces or other means.

FIG. 5

ROTARY DISC HAVING ADJUSTABLE ICE CHIP CUTTERS

BACKGROUND OF THE INVENTION

The present invention relates to improvement of ice cutting blades for use in systems for cutting a path through ice or maintaining a zone free of ice due to the action of rotating ice cutting blades.

In U.S. Pat. No. 3,521,592 to Rosner et al., there is provided an ice channel cutter for use on marine vessels. The cutter is mounted on the prow of the vessels and is provided with a plurality of vertically extending rotary ice engaging units each presenting an array of radially extending ice chopping blades or cutters. The ice choppers are rotated simultaneously with the forward movement of the vessel to chew into the ice and to chop it into relatively small chunks which are carried sideways and rearwardly around the vessel or downwardly such that the vessel may pass over it.

The ice engaging units are desirably movable, vertically relative to the vessel so as to position them for optimum efficiency independent of the depth the vessel may ride in the water due to its weight or load. As an optional feature, additional ice engaging units are pivotably mounted on opposite sides of the vessel adjacent the prow and adapted to be swung outwardly from the vessel to widen the channel initially cut by those units mounted on the vessel prow.

SUMMARY OF THE INVENTION

According to the present invention there is provided an improved ice chipping cutter for use in marine ice engaging units for cutting a path through ice.

The ice chip cutter of this invention consists of a disc for mounting on a rotatable shaft. A plurality of arm members containing ice chipping blades are pivotably mounted at one end thereof on the disc. The disc also provides means to control the extension of the ice chipping blades beyond the periphery of the disc during disc rotation and recesses to receive the ice chipping blades if an unusual resistance in the ice is met during disc rotation.

In one mode of operation, the ice chipping blades extend beyond the periphery of the disc to a controlled degree as a consequence of the centrifugal forces created by rotation of the disc. The extension of the ice chipping blades beyond the periphery of the disc is controlled by the stops on the disc which may be fixed or adjustable. If one or more of the blades meets an obstruction which cannot be cut, the blade is forced back into the recesses provided by the disc either totally or partially depending upon the resistance provided by the obstruction. When the obstruction has been passed or eliminated the blade returns to its normal position.

In optional embodiment, the arm members may be coupled to biased hydraulic system or other means which forces the arm member against the stops or controls the extension of the ice chipping blades without the use of a stop. This hydraulic system permits the ice chipping blades to retreat wholly or partially into the recesses of the disc when an obstruction is met and then force the ice chipping blades back to their desired position once the obstruction has passed.

THE DRAWING

FIG. 1 is a side view of the disc employing the adjustable ice chipping cutters.

FIG. 2 is a top view of FIG. 1 of the disc showing the ice chipping cutter mounted thereon in greater detail in both the extended and retracted positions of the ice chipping blades thereof showing fixed and adjustable stop means.

FIG. 3 illustrates side view of the preferred ice chipping arm member with ice chipping blade.

FIG. 4 illustrates the top view of an alternate system for various uses of a hydraulic mechanism to control the extension and retraction of the ice chipping blades of the ice chipping cutters.

FIG. 5 shows a detailed illustration of the hydraulic ice chipper return mechanism.

DESCRIPTION

According to the present invention, there is provided an adjustable ice chipper for use on structures mounted on vessels to cut a path through ice or for maintaining a zone around a fixed structure free of contact with ice or ice flows.

With reference first to FIG. 1 and FIG. 2, the adjustable ice chipper cutter consists of a disc 10 having slots 12 for mounting on a rotatable shaft passed through opening 14 by means of keys and the like.

On disc 10 there are positioned a plurality of ice chipping cutters 16 comprising pivotably mounted arm member 20 having secured thereto or as a part thereof ice chipping blades 22. The arm members 20 are pivotably secured to disc 10 in sliding relationship by shafts 24 and held in place by plates 26. Associated with each blade 22 there is provided on disc 10 recesses 28 which permits the blades 22 of pivotably mounted arm members 20 of ice chipping cutters 16 to retract into recess 28 when the ice chipping cutter 16 engages an object having a greater resistance than the cutting power provided to the blades 20 as a consequence of the centrifugal forces imparted to each ice chipping cutter 16 because of the rate of rotation of disc 10 about a shaft 40 (not shown).

There is also provided an ice chipping cutter stops which may be fixed such as pins 30 or adjustable such as a cam 31 which control the extension of the blade 22 of an ice chipping cutter 16 beyond the periphery 45 of disc 10, the stop engaging the opposed end of arm member 20 of ice chipping cutter 16.

With additional reference now to FIG. 3, ice chipping cutter 16 is provided with arm member 20 and blade 22. Arm member 20 permits blade 22 to extend beyond the periphery of disc 10.

In addition, the width of blade 22 is such that when one surface of arm member 20 is in contact or close relationship to disc 10, the outermost edge of blade 22 extends to and preferably beyond, as shown in FIG. 1, the width of disc 10.

The cutting edge 32 of blade 22 is preferably sharp in order that it will chip ice rather than cut ice since this requires less force. The arm member 20 of ice chipping cutter 46 is provided with opening 33 for mounting on shaft 24 of disc 10.

When employing the configuration illustrated in FIGS. 1, 2 and 3, a disc having a diameter of about 3 feet and rotated at a rate of 500 rpm will provide enough centrifugal force to hold the ice chipping cutter 16 against stop 30 or 31 and maintain a chipping action to chip ice of a high shear resistance for a cutter having a moment about shaft 24 of about 3 inches and a blade

edge 32 width of about 1.5 inches and arm member width of about 0.5 inch.

If the resistance exceeds this value or the cutting power of any ice chipping cutter 16, the cutter begins to retract into recess 28. The degree of retraction is dependent upon the resistance met and the ice chipping cutter 16 either is partially retracted to reduce the amount of bite blade 22 into the ice or entirely retracted into recess 28 as shown in FIG. 1 and FIG. 2.

Once the resistance has been overcome, centrifugal forces on the ice chipping cutter 16 as a consequence of the rate of rotation of disc 10 returns the cutter 16 to its normal position against stop 30 or 31.

With reference now to FIG. 4, there may be provided a biased system, preferentially hydraulic in nature which is fixed or pivotably secured to plate 10. This system provides a positive force against ice chipping cutter 16 but also permits retraction of the cutter when an unusual resistance is met.

Once the resistance is overcome, the bias force provided by system returns the ice chipping blade to its normal position against stop 30 or 31 when the resistance has been overcome. Return of the blade may be by action of system alone when it is secured to the ice chipping cutter 16 or by action of both system and centrifugal forces where the system is not secured to ice chipping cutter 16.

In the preferred embodiment the system comprises a cylinder 34 containing an hydraulic fluid 35 and a spring 37 which in combination provides a positive biased force and plunger shaft 36 provided with a disc 39 to provide resistance against retraction of shaft 36 and ice chipping blade 16. The system is, of course, provided with seal 41 to prevent fluid leakage. Where the plunger shaft 36 is secured to the ice chipping cutter 16, stop 30 may be eliminated as the biased plunger shaft 36 will control the extension of ice chipping blade 22 beyond the periphery of disc 10 and yet permit its retraction into recesses 28 as shown in FIG. 4, when an unusual resistance in the ice is met.

It will be appreciated that the addition of the biased system can increase the cutting power of the cutter over that provided only by centrifugal forces for the disc and cutter dimensions given above.

The adjustable ice chipping cutter of this invention may be constructed from mild steel although the ice chipping blades are preferably hardened for long wear.

What is claimed is:

1. An adjustable ice chipping cutter which comprises:
- a. a circular disc having upper and lower sides and a peripheral edge, said disc adapted to be rotatably secured to a shaft and provided with a plurality of

recesses about the peripheral edge thereof;

- b. a plurality of ice chipping cutters which cut ice

into chips pivotably secured to at least one side of

said disc in slidable relationship each ice chipping

cutter comprising:

- i. an arm member pivotably secured at one end of said disc in slidable relationship;
- ii. an ice chipping blade positioned along the length of said arm member and adapted by pivoting of said arm member to extend beyond the periphery of said disc and retreat into a recess thereof, said ice chipping blade having a sharp edge, said edge extending above and below the sides of said disc;
- c. means to control the extension of the ice chipping blades beyond the periphery of said disc.

2. An adjustable ice chipping cutter as claimed in claim 1 in which said means to control the extension of said ice chipping blade beyond the periphery of said disc comprises a plurality of cylinders each cylinder containing a hydraulic fluid and a spring biased against a shaft connected to an arm member, the natural extension of said shaft from said cylinder controlling the extension of said ice chipping blade beyond the periphery of said disc.

25 3. An adjustable ice chipping cutter as claimed in claim 1 in which the means to control the extension of the ice chipping blade beyond the periphery of said disc is a stop secured to said disc and positioned to engage the arm member at a point beyond said ice chipping

30 blade at point opposed to the end at which the arm member is pivotably secured to said disc.

35 4. An adjustable ice chipping cutter as claimed in claim 3 in combination with retractably biased means against said arm members to resist retraction of said ice

chipping blades into said recesses.

5. An adjustable ice chipping cutter as claimed in claim 4 in which each retractably biased means comprises a cylinder containing hydraulic fluid and a spring means biased against a shaft in contact with arm members.

40 6. An adjustable ice chipping cutter as claimed in claim 3 in which the stop is adjustable.

7. An adjustable ice chipping cutter as claimed in claim 6 in combination with retractably biased means 45 against said arm members to resist retraction of said ice chipping blades into said recesses.

8. An adjustable ice chipping cutter as claimed in claim 7 in which each retractably biased means comprises a cylinder containing hydraulic fluid and a spring means biased against a shaft in contact with arm members.
